BUILDING BLOCK

Joseph C. Conte, Rochester, N. Y.

Application April 11, 1957, Serial No. 45,700

Term of patent 14 years

(Cl. D18—2)

FIG. 2.

FIG. 1.

Figure 1 is a perspective view of a building block, showing my new design.

Figure 2 is a view of the left end of the building block on a slightly reduced scale from that of Figure 1.

The rear of the building block is plain and the end not shown is the same in appearance as that illustrated.

I claim:

The ornamental design for a building block, as shown and described.
